CLAIM

We claim the ornamental design for a portion of a container for wipes, as shown and described.

DESCRIPTION

FIG. 1 is a front view of a surface pattern for a container for wipes showing our new design.

FIG. 2 is a top view of the surface pattern along the line 2—2 of FIG. 1; and,

FIG. 3 is a top view of the surface pattern along the line 3—3 of FIG. 1.

The container for wipes is shown in broken lines for illustrative purposes only and forms no part of the claimed design.
